UNITED STATES PATENT OFFICE

158,395

SHOE

Normand P. Liberty, Farmington, N. H.

Application October 15, 1949, Serial No. 5,504

Term of patent 3½ years

(Cl. D7—7)

To all whom it may concern:

Be it known that I, Normand P. Liberty, a citizen of the United States of America, residing in Farmington, county of Stafford, and State of New Hampshire, have invented a new, original, and ornamental Design for a Shoe, of which the following is a specification, reference being had to the accompanying drawing, forming part thereof.

The figure on the drawing is a perspective view of a shoe, showing my new design.

The opposite side is substantially the same appearance as that shown.

I claim:

The ornamental design for a shoe, substantially as shown and described.

NORMAND P. LIBERTY.
